SEMISOFT BOX TOE FOR SHOES

Filed Nov. 18, 1925

Inventor:
William H. Baynard,
by his attorney Quincy May
Atty.s.

UNITED STATES PATENT OFFICE

WILLIAM H. BAYNARD, OF BOSTON, MASSACHUSETTS, ASSIGNOR TO HARRY H. BECKWITH, OF BROOKLINE, MASSACHUSETTS

SEMISOFT BOX TOE FOR SHOES

Application filed November 18, 1925. Serial No. 69,781.

Box toe stiffeners for shoes are now commonly formed of a fibrous base saturated with a thermoplastic material, so that by the application of a mild heat they may be softened preparatory to the pulling over and lasting operations, but will be relatively hard and stiff when at atmospheric temperature.

It is sometimes desired, however, to produce a flexible box which it is evident would not be produced by the use of a stiffener such as has been described. When the box is flexible throughout, however, it does not maintain its shape in use since the side walls are easily broken down.

According to the present invention, therefore, the stiffener is so constructed that when incorporated in the shoe its wall portions are stiff and hard as in the usual thermoplastic stiffened toe, but in which its roof is relatively soft and flexible comparable in this respect to the flexible or "soft" box. In order to produce this result the amount of thermoplastic material is caused to vary throughout the body of the stiffener, being in substantially the proportion relative to the base of the usual "hard stiffeners" along that portion which forms the wall of the box and being relatively much less over the remaining portion. Preferably also the less stiffened central portion at least is treated with material such as rubber to increase its springiness or tendency to resume a normal position when pressed therefrom.

While it might be possible to apply the thermoplastic material over that portion only of the stiffener which is to form the wall of the box, or more over that portion than elsewhere, a more convenient method comprises saturating the sheet material over its entire area and then skiving the box toe blank cut therefrom in such a manner as to remove some of the thermoplastic material over those portions which it is desired to render "soft". This method is particularly suitable if rubber is incorporated in the stiffener, as for example, according to the disclosure of the application for patent of W. B. Pratt for Box toes, filed May 25, 1925, Serial No. 32,576, in which the rubber is used as an ingredient of the thermoplastic treating

agent, or when the stiffener is first treated with rubber and then with the thermoplastic. The rubber remaining in the skived central portion of the stiffener which forms the roof of the box increases the natural springiness of the more flexible portion.

For a more complete understanding of this invention, reference may be had to the accompanying drawings in which—

Figure 1 is a plan of a stiffener blank.

Figure 2 shows the same blank after being skived according to this invention.

Figures 3 and 4 are sections on lines 3—3 and 4—4, respectively, of Figure 2.

Figure 5 is similar to a portion of each of Figures 3 and 4, but is drawn to an enlarged scale.

Figure 6 is a longitudinal section through the toe portion of a shoe having a stiffener constructed according to this invention.

Figure 7 is a section on line 7—7 of Figure 6.

A sheet of the foundation fibrous material is first saturated with a thermoplastic compound and then is cut, as by dies, to form single sheet stiffener blanks as shown at 1 in Figure 1. This blank is then skived, as shown in Figures 2, 3, 4 and 5, to produce a tapered margin, as at 2 and 3, and a central portion of the surface is also removed over that portion of the stiffener which when in use will form the roof of the box, this being indicated at 5 so as to leave the full thickness of the material only over an arc shaped zone or portion 4 which extends about the more sharply curved end of the blank substantially parallel with its edge. When the fabric is saturated with the thermoplastic compound more of this compound becomes deposited adjacent to the outer faces of the sheet, as indicated by the more heavily shaded portions 10 and 11 of Figure 5. During the skiving operation the more heavily treated portion on one side of the blank is removed, as shown clearly in Figure 5, so that not only is the blank made thinner except over the portion 4 by the skiving treatment, but also a considerable amount of the thermoplastic material is removed. Thus the arcuate portion 4 is of the maximum stiffness and rigidity while

the margins and the portion within the zone 4 is much poorer in thermoplastic material. If, however, rubber has been used either in a pretreatment or as a constituent of the 5 stiffening agent, the rubber remaining in the central portion of the blank acts to render this portion springy and elastic so that if the 10 roof of the finished box toe is deformed somewhat by pressure, it will immediately spring back to proper shape when such pressure is released.

This blank is softened by heat in the usual manner and lasted into the shoe as shown in Figures 6 and 7, the skived marginal portions 15 2 about the more sharply curved end of the blank being engaged by the inseam stitches 15 (in the case of a welt shoe), the portion 5 forming the roof of the box. This roof portion when the stiffener has become 20 "set" may be deformed as by depressing it inwardly as shown by dotted lines in Figures 6 and 7, without however causing the side wall portions 4, which are relatively stiff and hard, to yield or be broken down, and as 25 soon as this pressure is removed the roof portion immediately returns to its proper position.

Having thus described an embodiment of this invention, it should be evident to those 30 skilled in the art that various changes and modifications may be made therein without departing from its spirit or scope as defined by the appended claims.

I claim:

35 1. A toe stiffener for shoes comprising a single sheet of material having its wall portion normally relatively stiff and its roof normally relatively flexible.

40 2. A toe stiffener comprising a single sheet of fibrous sheet material saturated with a thermoplastic stiffening agent, there being a relatively large amount of stiffening agent in the wall portion of the stiffener and a relatively small amount in substantially its entire 45 roof portion.

45 3. A toe stiffener comprising a single sheet of fibrous sheet material treated with a thermoplastic and rubber, there being a relatively large amount of thermoplastic in its wall 50 portion and a relatively small amount of thermoplastic in substantially its entire roof portion.

55 4. A toe stiffener comprising a single sheet of normally stiff material relatively thick at its wall portion and relatively thin over substantially its entire roof portion.

60 5. A toe stiffener comprising a single sheet of thermoplastic saturated material having a relatively thick wall portion and which is relatively thin over its entire roof portion.

65 6. A toe stiffener comprising a single sheet of fibrous foundation material saturated with a thermoplastic, said stiffener being relatively thick and normally stiff about its wall por-

tions and relatively thin and flexible over substantially its entire roof portion.

7. A toe stiffener comprising a single sheet of fibrous foundation material saturated with stiffening agent, the amount of such stiffening agent being relatively large in the wall portions of said stiffener and relatively small in substantially its entire roof portion. 70

8. The step in the formation of a box toe stiffener which comprises skiving over substantially the entire portion which is to form the roof of the box a blank previously treated with a thermoplastic stiffening agent whereby its normal stiffness at such roof is reduced. 75

9. That step in the formation of a box toe stiffener which comprises skiving a normally stiff blank of sheet material about its margin and over substantially the entire portion which is to form the roof of the box, whereby the normal stiffness of such skived portions 80 is reduced. 85

10. Steps in the formation of a box toe stiffener which comprise saturating a piece of absorbent sheet material with thermoplastic material, the saturant being deposited in 90 layers of varying concentration, and removing from the central roof portion of a stiffener blank a layer having greater than average concentration of saturant.

In testimony whereof I have affixed my 95 signature.

WILLIAM H. BAYNARD.
